UNITED STATES PATENT OFFICE.

CORNELIUS B. CORCORAN, OF NEW YORK, N. Y., ASSIGNEE TO UNDERWOOD TYPE-WRITER COMPANY, OF NEW YORK, N. Y., A CORPORATION OF DELAWARE.

TYPE-WRITING MACHINE.

1,105,184.

Specification of Letters Patent. Patented July 28, 1914.

Application filed August 14, 1912. Serial No. 715,084.

To all whom it may concern:

Be it known that I, CORNELIUS B. CORCORAN, a citizen of the United States, residing in the borough of Bronx, city of New York, in the county of New York and State of New York, have invented certain new and useful Improvements in Type-Writing Machines, of which the following is a specification:

10 This invention relates to the paper-controlling devices of typewriting machines, and its principal object is to provide means for facilitating the insertion and gaging of the work sheet or sheets.

15 When introducing work-sheets rearwardly with lower edge foremost at the front side of the platen of a front-strike writing machine, some difficulty has been encountered because of the usual arrangement of the ribbon vibrator in front of the platen and almost in contact therewith. There is liability of the work-sheet fouling upon the ribbon vibrator, and to some extent the same is true of the usual center guide for the type-bars, which is arranged just below the printing point. As a means for overcoming this difficulty, I have arranged a paper-guiding chute or deflector at the front of the platen, rigidly placed to one side of the machine so

20 far as to be entirely to one side of both the type guide and the ribbon vibrator; so that, by running the carriage over, say to the extreme limit of its leftward travel, the work-sheet may be conveniently introduced between the guiding chute and the platen, and run backwardly around the under side of the platen, and then gripped by the feed rolls or devices, whereupon the carriage may be returned to the right, to begin the line of

25 writing. In this way, all liability of fouling of the work-sheet upon the ribbon guide or the type guide, is avoided.

For the purpose of the invention, there may be used a carriage of super-width in proportion to the width of the work-sheet; or, in other words, a machine having an extra-wide carriage may be employed for writing upon a sheet of ordinary size. This will permit the carriage to be set far enough to the left to permit the introduction in this way of a sheet of common size. The devices under the platen for guiding the work-sheet need to be only as wide as the sheet; and said chute may be of a length substantially equal to the length of the ordinary printing

field on the platen. A wide carriage machine may be readily employed for introducing and writing upon work-sheets of ordinary width, whenever it is desired to introduce the sheets at the front of the platen; and, whenever required, the same carriage can also be employed for writing in the ordinary way upon extra-wide sheets introduced in the usual manner at the rear of the platen.

Under the arrangement of a wide carriage referred to in this application, wherein the front introductory chute is arranged completely at one side of the printing center for use only when the carriage is at one extreme end of its travel, the platen is shown as having a surplus longitudinal portion in addition to that portion thereof comprising the printing field adapted to move into and out of the paper-introducing part of said front chute. That surplus portion, while an extension of said printing field and serviceable therewith in providing the wide printing field of the platen for employment in conjunction with the usual rear paper-feed mechanism, plays no part in the operative association between the front introductory chute and the printing field and feed devices therefor, and does not in the carriage-shifting movements at any time enter the paper-guiding path of said front chute. Hence the printing field of the platen which carries work-sheets received from the front introductory chute, may be distinguished as the front feed printing field of the platen, in contradistinction to the wide field of the entire platen, for use with the rear feeding devices. Said deflector or chute, in its fixed position, in which it is spaced apart from the platen, is always capable of coöperating with guiding devices mounted on the carriage itself and extending around the under side of the platen to the front thereof; said guiding devices being normally close to the platen, but being releasable, so that they may be dropped to a position to coöperate with said chute. These guiding devices may comprise the usual rolls which run upon the under surface of the platen, and a guiding plate or apron which curves around the under side of the platen, both said rolls and apron being mounted so as to be capable of being dropped downwardly from the platen in order to be brought into alinement or operative register with the chute or deflector.

Preferably the releasing of the pressure

rolls and platen apron are effected automatically by moving the paper carriage to the extreme of its run; a cam upon the machine frame being engaged by a roll-releasing pin upon the carriage; and the apron being then brought to position to coöperate with said chute.

Above the platen is provided a gaging tablet upon which the leading edge of the work sheet may be gaged after its bottom edge has been inserted around the platen as aforesaid; and while the sheet is held to the gage, the bottom pressure rolls may be restored to the platen so as to hold the sheet and permit the latter to be advanced independently of the gage. Pressure rolls are also arranged to run upon the platen between the platen and said gage tablet, and the latter is preferably cut away to afford a clearance for the roll structures. The gage tablet is adjustable along the platen and is also movable by means of a finger-piece upwardly away from the platen (together with the top rolls) and to permit the introduction of a work sheet between the platen and said rolls and tablet.

Other features and advantages will hereinafter appear.

In the accompanying drawings, Figure 1 is a perspective plan of an Underwood wide-carriage front-strike writing machine provided with the present improvements, and showing the parts ready for the insertion of sheets at the front of the platen. Fig. 2 is a sectional side elevation, showing the top pressure rolls and the top gage plate swung away from the platen to permit the work sheet to be carried back over the platen. At this figure, the lower pressure rolls are shown in working positions. Fig. 3 is a front elevation of a portion of the pressure-roll mechanism, showing particularly the guides and supports for the paper-guiding apron which curves around under the platen. Fig. 4 is a view similar to Fig. 2, but showing the top feeding rolls and paper-gaging tablet or tablet in normal positions; the bottom pressure rolls being, however, released, together with the paper-guiding apron, for the insertion of work sheets at the front of the platen. Fig. 5 is a front elevation, showing details of construction of mounting of the top pressure rolls and paper gage plate. Fig. 6 shows a fragmentary front view of a cam fixed on the typewriter framework in the path of a projection which is mounted on a rotary rod on the typewriter carriage, whereby the cam, by reason of the travel of the carriage in letter-feeding direction, may rotate the rod for the purpose of releasing the bottom pressure rolls and the bottom paper guiding apron when the carriage reaches position for coöperation with the sloping paper-guiding plate fixed on the framework in front of the platen, as

at Fig. 4. Fig. 7 shows the positions of the parts effected by the cam at Fig. 6.

The cylindrical platen 1, which is shown of extra length, although shorter platens may be used, is journaled by an axle 2 in the ends 3, 4 of a platen frame, which comprises a rear paper shelf 5 connecting said ends, and also comprises a tie-rod 6 extending between said ends. The platen frame is mounted by suitable means (not shown) upon a carriage 7 which runs upon the usual forward and rear tracks 8, 9.

The system of pressure rolls running upon the under side of the platen to carry the work sheet around the same may be of the usual construction, comprising rear rolls 10 mounted on shaft 11, and front rolls 12 mounted on shaft 13; shaft 11 being carried on arms 14, and shaft 13 being carried on arms 15; all of said arms journaled on tie-rod 6. Upon said rod 6 are also mounted leaf springs 16, 17, to engage respectively the arms 14, 15, whereby the rolls 10, 12 are pressed against the platen. The pressure rolls may be released in the usual manner by means of a key 18 pivoted at 19 on the platen frame and connected by a link 20 to an arm 21 on rock shaft 22, which is journaled on the platen frame and extends along the platen between arms 23 formed on said roll-carrying arms 14, 15; the arms 23 normally occupying recesses 24. When said rock shaft 22 is rotated, the arms 23 are forced apart, as at Fig. 4, thus pulling down the arms 14, 15, together with the rolls 10, 12, and leaving a clearance between said rolls and the platen 1 for the introduction and adjustment of the work sheets. Owing to the cylindrical shape of the shaft 22, the arms 23 are mechanically locked apart in their released positions at Fig. 4.

One of the objects of the invention being to facilitate the introduction of the work sheets at the front of the platen, the guiding apron 25, which curves around the under side of the platen in conformity therewith, is arranged to drop, especially at its front edge, whenever the pressure rolls 10, 12 are released, as at Fig. 4, so as to leave an opening of substantial size between the platen and the front edge of said guiding apron for the introduction of sheets. This guiding apron may be unattached at either of its front and rear edges; but it may have at each end a guiding yoke 26 to set down loosely over the rod 6, and at its front and rear edges it may rest on small rolls 27 on the shafts 11, 13; this guiding plate being recessed at its front and rear edges at 28 to accommodate the pressure rolls, Fig. 3. By means of hooks 29 at the ends of this paper apron catching under arms 15, said apron is drawn down at its front edge to the Fig. 4 position when the pressure rolls are released, so that it registers with or falls slightly be-

low a long sloping introductory guide plate 30 fixed upon the machine frame preferably at the left hand side of the usual type bar system 31, Fig. 1.

5 When the carriage is drawn to the left, as at Fig. 1, and the parts are in their released positions in Fig. 4, it is a simple matter to drop in a work sheet, bottom edge foremost, as indicated by the arrow at Fig. 4, the plate 30 coöperating with the platen to form a narrowing throat to receive the sheet; and the apron 25 coöperating with the under side of the platen to form a continuation of said throat to guide the sheet backwardly 15 and upwardly as far as may be desired; the lower edge of the paper shelf 5 being preferably curved back at 32 to prevent the rising edge of the work sheet from catching thereon. The introductory guiding plate 30 20 may project from a bracket 33 fixed by means of screws to the framework.

In operation, the carriage 7 is moved to the left as far as it will go, thereby bringing into use the introductory guide plate or 25 chute 30 at the front of the platen. During this movement of the carriage, a pin or lug 34 projecting from the roll-releasing shaft 22, Fig. 6, may engage a fixed cam 35 and ride up along the same, Fig. 7, thereby rock- 30 ing the shaft 22 and releasing the rolls and dropping the paper apron to the Fig. 4 position; said cam being preferably mounted upon an arm 36 extending from bracket 33 and having a screw 37 to bear upon the 35 framework 38 of the typewriter to adjust the cam 35 to the proper position. The operator then inserts the work sheet or sheets, bottom foremost, as shown by the arrow at Fig. 4, between the plate 30 and the platen 1, 40 and then backwardly between the platen and the apron 25, then upwardly along the paper shelf 5. Then the operator adjusts the top edge of the work sheet 39 to a top gage 40 and side gage 41 provided upon a tablet 42 arranged above the platen, so that the work 45 sheet is adjusted edgewise in both directions. Without disturbing this adjustment, the operator may run the carriage 7 back to release the pin 34 from the cam 35, so that the 50 springs 16, 17 may restore the pressure rolls 10, 12 and secure the work sheet 39 where adjusted; whereby the operator has succeeded in bringing the sheet mechanically to a predetermined position with reference 55 to the printing point on the platen.

The lug 34, it will be understood, is set so that it does not, while riding along the cam 35, rotate the releasing shaft 22 to the mechanical locking position thereof, seen at 60 Fig. 4, but falls short of doing so, (Fig. 7) so that a mere return movement of the carriage 7 to the right will permit the springs 16, 17 to restore the pressure rolls and guiding plate 25. The operator now depresses 65 a lever 43 to throw up the top pressure rolls

44 (together with the top gage tablet 42) to clear the platen, so that the top edge of the work sheet 39 may be thrust backwardly above the platen and below the rolls 44, as seen at Fig. 2; the work sheet being held fast 70 against the platen by the rolls 10, 12. The operator then restores the finger lever 43 to bring the rolls 44 down upon the work sheet to press it against the platen; whereupon the writing of the work sheet line by line 75 may proceed in the usual manner. The finger lever 43 is fixed upon a rock shaft 45 mounted in bearings or brackets 46 fixed upon the platen frame ends 3, 4. Along the under side of the rock shaft 45 extends a longitudinal groove 47, Fig. 5, into which cylindrical keys 48 are pressed by springs 49, to hold the rock shaft yieldingly in normal position.

The top rolls 44 are mounted by means 85 of arms 50 upon brackets 51 which have arms 52, 53 perforated to fit on the rock shaft 45; the brackets being held in proper relation to said rock shaft by keys 54 and springs 55; each bracket being releasable by 90 pressing downwardly an extension 56 formed on the arm 53. The arms 50 are yielding, and the tension of each spring may be regulated by means of a thumb screw 57 threaded through an ear 58 provided upon 95 the bracket 51 and bearing down on the arm 50. The gage plate or tablet 42 is cut away between its ends at 59 for the principal portion of the length of the plate, so as to make room for the rolls 44 and screws 100 57, so that said rolls may bear down upon a work-sheet that has previously been adjusted to the plate in the manner already explained. Each roll bracket 51 is adjustable along the rock shaft 45 independently 105 of the other.

The gage plate or tablet 42 is supported at or near its ends by a pair of brackets 60 which are similar to the bracket 51, and are held to the rock shaft 45 by springs and 110 keys similar to the springs 55 and keys 54. Each bracket 60 has an arm 63 to which an ear 61 is adjustably connected by a pivot 64. The gage tablet 42 is connected to the ears 61 by screws 62 passing through slots in the 115 tablet and threaded into the ears 61, thereby permitting up and down adjustment of the tablet relative to the brackets 60. The tablet gage is also angularly adjustable with the ears 61 about the pivots 64; and the 120 joint is made tight to hold firmly the paper-gaging tablet in any position to which it may be adjusted on said pivot. The paper table is therefore independently adjustable in normal position to give it the right relationship to the platen; and it preferably may be swung up around the rock shaft 45 independently of the rolls 44; while it may at any time, by depressing the arm 43, be 125 swung up to the Fig. 2 position together 130

with the rolls 44. Moreover, the bracket 60, together with the gaging tablet, may be adjusted along said rock shaft 45 to permit work to be done at different parts of the platen 1.

Whenever desired, a record sheet may be inserted around the platen in the usual manner before any of the statements or blanks 39 are inserted; the record sheet being usually longer than the statements, and being indicated at 39^a, Fig. 4. It will be understood that a carbon usually overlies this record sheet; both the carbon and the record sheet being always under the control of the rolls 44, so that they are properly fed line by line as the platen rotates. When the record sheet 39^a is employed, the work sheets or statements 39 do not need to be introduced between the rolls 44 and the platen 1, but instead may ride up over the top of the gage 40. However, it is obvious that the rolls 44 may be swung up while the bottom rolls 10, 12 are in working positions, as at Fig. 2, so that the bottom rolls may hold the record sheet 39^a, while the top rolls 44 are released to admit the statement 39. The work sheet 39 may, of course, consist of several blanks with interposed carbons.

Variations may be resorted to within the scope of the invention, and portions of the improvements may be used without others.

Having thus described my invention, I claim:

1. The combination of a revoluble platen, pressure rolls running upon the under side of the same, means to release said pressure rolls, a paper-guiding apron curving around the under side of the platen and connected to be dropped when said rolls are released, and a separate sloping stationary deflector or guide forward of the platen and permanently spaced apart from the platen in position to coöperate with said apron, when the latter is dropped, to guide the bottom edges of sheets downwardly and backwardly under the platen.

2. The combination of a revoluble platen, pressure rolls running upon the under side of the same, means to release said pressure rolls, a paper-guiding apron curving around the under side of the platen and connected to be dropped when said rolls are released, and a separate stationary sloping deflector or guide forward of the platen and permanently spaced apart from the platen in position to coöperate with said apron, when the latter is dropped, to guide the bottom edges of sheets downwardly and backwardly under the platen; said sloping deflector or shelf mounted upon the fixed frame of the machine, and said platen mounted upon a carriage.

3. The combination of a revoluble platen, pressure rolls running upon the under side of the same, means to release said pressure

rolls, a paper-guiding apron curving around the under side of the platen and connected to be dropped when said rolls are released, and a separate stationary sloping deflector or guide forward of the platen and permanently spaced apart from the platen in position to coöperate with said apron, when the latter is dropped, to guide the bottom edges of sheets downwardly and backwardly under the platen, said sloping deflector or shelf mounted upon the fixed frame of the machine, and said platen mounted upon a carriage; said deflector being mounted at one side of the printing point, so that it may coöperate with said apron when the carriage is shifted to one extreme of its run.

4. The combination of a revoluble platen, pressure rolls running upon the under side of the same, means to release said pressure rolls, a paper-guiding apron curving around the under side of the platen and connected to be dropped when said rolls are released, and a separate sloping deflector or guide forward of the platen and normally ineffective but in position to coöperate with said apron, when the latter is dropped, to guide the bottom edges of sheets downwardly and backwardly under the platen, said sloping deflector or shelf mounted upon the fixed frame of the machine, and said platen mounted upon a carriage; said deflector being mounted at one side of the printing point, so that it may coöperate with said apron when the carriage is shifted to one extreme of its run; said roll-releasing means including a part automatically brought into conjunction with a fixed part on the frame when the carriage is so shifted for operation thereby.

5. In a typewriting machine, the combination with a carriage, of a revoluble platen mounted on said carriage, feed rolls to run upon the platen, yielding means upon said carriage normally pressing said rolls against the platen, a finger-piece upon said carriage to release said rolls, means upon the framework of the machine to release said rolls when the platen has been carried beyond the printing field, whereby when the carriage is in the printing field the finger-piece may be manipulated at any time to release the sheets, and whereby when the carriage has traveled beyond the printing field the work-sheet may be pulled out and another substituted without manipulating said finger-piece, and a guide mounted upon the frame work of the machine to coöperate with the platen when the carriage has traveled to roll-releasing position, for coöperation with said platen to guide sheets introduced bottom end foremost down around the front side of the platen.

6. The combination of a revoluble platen, pressure rolls running thereon, a carriage for said platen, means dependent upon the

- movement of the carriage for automatically releasing said rolls, paper-guiding means extending around said platen and connected to be released together with said rolls, and 5 a fixed sloping deflector or guide so mounted and permanently spaced from the platen that it can coöperate with said paper-guiding means whenever the carriage is moved to position to release said rolls.
- 10 7. The combination of a carriage, a revoluble platen, pressure rolls running on the platen, a fixed cam, roll-releasing means on the carriage and including a part to engage said fixed cam, paper-guiding means upon 15 the under side of said platen, and a sloping deflector or chute upon the machine frame so mounted and permanently spaced from the platen that it can coöperate with said paper-guiding means whenever the carriage 20 is moved to roll-releasing position.
8. The combination of a revoluble platen, a paper-gaging tablet in proximity to the platen above the printing point and provided with means movable into and out of 25 position to gage the top edge of a work-sheet, means in front of and under the platen for guiding a sheet bottom foremost downwardly and backwardly around the platen, preparatory to gaging the top edge 30 of said sheet on said tablet, and pressure rolls to run on the platen below the printing point, movable away from the platen to permit the insertion and gaging of the sheet, and returnable to the platen while the sheet 35 is held against the gage.
9. The combination of a revoluble platen, a paper-gaging tablet in proximity to the platen above the printing point and provided with means to gage the top edge of a 40 work-sheet, means in front of and under the platen for guiding a sheet bottom foremost downwardly and backwardly around the platen, preparatory to gaging the top edge of said sheet on said tablet, pressure rolls 45 to run on the platen below the printing point, movable away from the platen to permit the insertion and engagement of the sheet, and returnable to the platen while the sheet 50 is held against the paper-gaging tablet, a carriage upon which said platen is mounted, and means dependent upon the movement of said carriage for automatically controlling said pressure rolls.
10. The combination of a revoluble platen, 55 a paper-gaging tablet in proximity to the platen above the printing point and provided with means to gage the top edge of a work-sheet, means in front of and under the platen for guiding a sheet bottom foremost 60 downwardly and backwardly around the platen, preparatory to gaging the top edge of said sheet on said tablet, pressure rolls to run on the platen below the printing point, movable away from the platen to permit the 65 insertion and engagement of the sheet, and
- returnable to the platen while the sheet is held against the paper-gaging tablet, a carriage upon which said platen is mounted, and means dependent upon the movement of said carriage for controlling said pressure 70 rolls; said paper-guiding means including a guide or chute mounted upon the machine frame in position to coöperate with a member mounted upon the carriage in proximity to the platen when the carriage is moved to 75 roll-releasing position.
11. The combination of a revoluble platen, a paper-gaging tablet in proximity to the platen above the printing point, means in front of and under the platen for guiding a sheet bottom foremost downwardly and backwardly around the platen, preparatory to gaging the top edge of said sheet on said tablet, pressure rolls to run on the platen below the printing point, movable away 80 from the platen to permit the insertion and engagement of the sheet, and returnable to the platen while the sheet is held against the gage, a carriage upon which said platen is mounted, and means dependent upon the movement of said carriage for controlling said pressure rolls; said paper-guiding means including a guide or chute mounted upon the machine frame in position to coöperate with a member mounted upon the carriage in proximity to the platen when the carriage is moved to roll-releasing position; said gage-plate mounted for movement away from the platen, to permit the leading edge of the work sheet to be passed backwardly between the gage tablet and the platen. 85
12. The combination with a revoluble platen, of a platen frame, a rock-shaft mounted on the platen frame and extending 90 along the platen, a paper-gaging tablet mounted on said rock-shaft, a key connected to said rock-shaft to swing said tablet away from the platen, and means to hold said rock-shaft in normal position. 95
13. The combination with a revoluble platen, of a platen frame, a rock-shaft mounted on the platen frame and extending along the platen, a paper-gaging tablet mounted on said rock shaft, a key connected 100 to said rock-shaft to swing said tablet away from the platen, means to hold said rock-shaft in normal position, and a sheet-guiding pressure roll also mounted on said rock-shaft to be swung with said tablet. 105
14. The combination with a revoluble platen, of a paper-gaging tablet mounted above the platen, and pressure rolls between the tablet and the platen. 110
15. The combination with a revoluble platen, 115 of a paper-gaging tablet mounted above the platen, and pressure rolls between the tablet and the platen; said tablet cut away for clearance for the pressure rolls. 120
16. The combination with a platen, of a 130

rock-shaft extending therealong and having a longitudinal groove, brackets having spring-pressed keys engaging said groove and rotatable upon said rock-shaft independently thereof, ears on said brackets, a paper-gaging tablet adjustably pivoted on said ears and firmly held thereby in adjusted positions, a finger-piece to rock said shaft together with said tablet away from the platen, and means to hold said rock-shaft in normal position.

17. The combination with a platen, of a rock-shaft extending therealong and having a longitudinal groove, brackets having spring-pressed keys engaging said groove and rotatable upon said rock-shaft independently thereof, ears on said brackets, a paper-gaging tablet adjustably pivoted on said ears and firmly held thereby in adjusted positions, a finger-piece to rock said shaft together with said tablet away from the platen, means to hold said rock-shaft in normal position, and roll-carrying arms also mounted on said rock-shaft to be swung away from and back to the platen together with said gaging tablet.

18. The combination with a platen, of a rock-shaft extending therealong and having a longitudinal groove, brackets having spring-pressed keys engaging said groove and rotatable upon said rock-shaft independently thereof, ears on said brackets, a paper-gaging tablet adjustably pivoted on said ears and firmly held thereby in adjusted positions, a finger-piece to rock said shaft together with said tablet away from the platen, and means to hold said rock-shaft in normal position; said tablet adjustable along said rock-shaft.

19. The combination with a platen, of a rock-shaft extending therealong and having a longitudinal groove, brackets having spring-pressed keys engaging said groove and rotatable upon said rock-shaft independently thereof, ears on said brackets, a paper-gaging tablet adjustably pivoted on said ears and firmly held thereby in adjusted positions, a finger-piece to rock said shaft together with said tablet away from the platen, means to hold said rock-shaft in normal position, and roll-carrying arms also mounted on said rock-shaft to be swung away from and back to the platen together with said gaging tablet; said tablet and said roll-carrying arms adjustable along said rock shaft.

20. The combination with a rotatable platen and a platen frame, of a rock shaft journaled on the ends of said frame, pressure rolls carried by said shaft, and a paper gaging tablet on said shaft.

21. The combination with a rotatable platen and a platen frame, of a shaft located over the platen and supported on the ends of said frame, pressure rolls carried by said

shaft and bearing against the platen, and a paper-gaging tablet mounted on said shaft.

22. The combination with a rotatable platen and a platen frame, of a rock shaft mounted on the frame above the platen, pressure rolls carried by the rock shaft and bearing against the platen, and a paper gaging tablet supported on said shaft and located above the pressure rolls.

23. The combination with a rotatable platen and a platen frame, of a shaft located over the platen and parallel therewith, and a paper-gaging tablet mounted on said shaft with its paper-supporting face substantially in a plane tangent to the platen.

24. The combination with a rotatable platen and a platen frame, of a shaft located over the platen and parallel therewith, a paper-gaging tablet mounted on said shaft with its paper-supporting face substantially in a plane tangent to the platen, pressure rolls carried by said shaft and located behind said plane, and means to rock the shaft and carry said rolls away from the platen.

25. The combination with a revoluble platen having a guiding apron normally in operative position relatively thereto, of an introductory deflector permanently stationed in position in advance of the forward surface of said platen to guide work-sheets to said apron, and means for moving said apron away from said platen in position to receive work-sheets from said deflector.

26. The combination with a revoluble platen having pressure rolls normally in contact therewith, of an introductory deflector permanently stationed in position in advance of the forward surface of said platen to guide work-sheets to said pressure rolls, and means for moving said pressure rolls away from said platen in position to receive work-sheets from said deflector.

27. The combination with a revoluble platen having a guiding apron and pressure rolls normally in operative position relatively thereto, of an introductory deflector permanently stationed in position in advance of the forward surface of said platen to guide work-sheets to said apron and pressure rolls, and means for moving said apron and pressure rolls together from said platen in position to receive work-sheets from said deflector.

28. The combination with a revoluble platen having a guiding apron normally in operative position relatively thereto, of an introductory deflector permanently stationed in position in advance of the forward surface of said platen to guide work-sheets to said apron, means for moving said apron away from said platen in position to receive work-sheets from said deflector, and a carriage for said platen, said deflector being mounted at one side of the printing point so

that it may coöperate with said apron when the carriage is shifted to one extreme of its run.

29. The combination with a revoluble platen having pressure rolls normally in contact therewith, of an introductory deflector permanently stationed in position in advance of the forward surface of said platen to guide work-sheets to said pressure rolls, means for moving said pressure rolls away from said platen in position to receive work-sheets from said deflector, and a carriage for said platen, said deflector being mounted at one side of the printing point so that it may coöperate with said rolls when the carriage is shifted to one extreme of its run.

30. In a front-strike typewriting machine having a framework, the combination of a revoluble platen, a carriage for said platen, paper-guiding means extending around the under side of the platen to the front thereof, and an introductory chute mounted upon the framework of the machine in front of the platen, and displaced wholly to one side of the printing point in position to be of use when the carriage is at only one extreme portion of its travel; said platen having a certain length of printing field which agrees with the length of said chute, to register and coöperate therewith, and said carriage being movable to carry all of said length of printing field far to one side of the printing center, to bring said length of printing field and chute into proper relationship, so that a sheet introduced by means of the chute may entirely cover said length of printing field.

31. In a front-strike typewriting machine having a framework, the combination of a revoluble platen, a carriage for said platen, paper-guiding means extending around the under side of the platen to the front thereof, and an introductory chute mounted upon the framework of the machine in front of the platen and displaced wholly to one side of the printing point in position to be of use when the carriage is at only one extreme portion of its travel; said platen having a certain length of printing field which agrees with the length of said chute, to register and coöperate therewith, and said carriage being movable to carry all of said length of printing field far to one side of the printing center, to bring said length of printing field and chute into proper relationship, so that a sheet introduced by means of the chute may entirely cover said length of printing field, said paper-guiding means being releasable, and said chute being in position to coöperate with said paper-guiding means only when the latter is released.

32. In a front-strike typewriting machine

having a framework, the combination of a revoluble platen, a carriage for said platen, paper-guiding means extending around the under side of the platen to the front thereof, and an introductory chute mounted upon the framework of the machine in front of the platen, said platen having a front feed printing field adapted in the extreme movement of the carriage in one direction to enter the path of said introductory chute and receive the work-sheet therefrom.

33. The combination with a revoluble platen, a carriage therefor, and a releasable paper guide extending around the under side of the platen to the front portion thereof, of a chute mounted upon the machine frame in front of the carriage in position to coöperate with said paper guide only when the latter is released.

34. The combination with a revoluble platen, of a platen frame, a tablet having side and top gages to square and limit the work-sheet, movable means supporting said tablet normally in operative position with respect to the platen, and a key connected with said movable means to swing said tablet out of said operative position.

35. The combination with a revoluble platen, of a platen frame, a tablet having side and top gages to square and limit the work-sheet, movable means supporting said tablet normally in operative position with respect to the platen, a key connected with said movable means to swing said tablet out of said operative position, and means to hold said movable means with the tablet in normal position.

36. The combination with a revoluble platen, of a platen frame, a tablet having side and top gages to square and limit the work-sheet, movable means supporting said tablet normally in operative position with respect to the platen, a key connected with said movable means to swing said tablet out of said operative position, means to hold said movable means with the tablet in normal position, and a sheet-guiding pressure roll also mounted on said movable means to be swung with said tablet.

37. The combination with a rotatable platen and a platen frame, of a shaft located over the platen and parallel therewith, and a paper tablet having side and top gages to square and limit the work-sheets, mounted on said shaft with its work-sheet supporting face substantially in a plane tangential to the platen.
